DESIGN FOR A COMBINED LAMP AND COSMETIC CONTAINER

William Minkin, Brooklyn, N. Y.

Application July 18, 1936, Serial No. 63,926

Term of patent 3½ years

To all whom it may concern:

Be it known that I, William Minkin, a citizen of the United States, residing at Brooklyn, New York, in the county of Kings and State of New York, have invented a new, original, and ornamental Design for a Combined Lamp and Cosmetic Container, of which the following is a specification, reference being had to the accompanying drawing, forming a part thereof:

Fig. 1 is a side elevational view of a combined lamp and cosmetic container, showing my new design.

Fig. 2 is a perspective view thereof with the base portion removed.

Fig. 3 is a perspective view of the base portion thereof showing how it appears when serving as a cosmetic container.

I claim:

The ornamental design for a combined lamp and cosmetic container, as shown and described.

WILLIAM MINKIN.
